MONROE E. MILLER, OF WASHINGTON, DISTRICT OF COLUMBIA, ASSIGNOR, BY MESNE ASSIGNMENTS, TO UNION SIMPLEX TRAIN CONTROL CO., INC., OF ROCHESTER, NEW YORK, A CORPORATION OF DELAWARE.

RUN-DOWN AND RESET LOCOMOTIVE-CONTROL APPARATUS.

Application filed January 15, 1923. Serial No. 612,780.

The present invention relates to automatic apparatus for controlling the movement of locomotives, street cars or other self-propelled vehicles that travel along tracks, and is more particularly an improvement in the run-down and reset type of control, wherein means are provided for retarding or stopping the locomotive when it has travelled a predetermined distance unless such means are reset at designated intervals, thereby requiring impulses or indications from the track elements to keep the locomotive running.

The primary object of the invention is to obtain practically continuous control of the locomotive according to track conditions, in order that the locomotive may be automatically slowed down or stopped while travelling in a block, and then permitted to proceed, with or without speed control, if traffic conditions permit, without waiting until the end of the block is reached for a clear or proceed indication, to facilitate traffic and avoid congestion by unduly retarded movements. The present apparatus is a compromise between what is known as "intermittent or block entrance initiated control" and "continuous control", having advantages of both and eliminating certain disadvantages of each of them.

Another object of the invention is the provision of a run-down and reset locomotive control apparatus enabling several different conditions to be obtained while the locomotive is moving along the track, either in a block or from one block to another, such as the establishment of a caution condition and restricted speed control, in addition to a danger or locomotive stopping condition.

Another object is the provision of such an apparatus which enables a clear or free running condition to be obtained while proceeding under speed restriction, and while traveling in a block, so that if the locomotive is travelling under danger speed control a caution speed control condition can be established, and if the locomotive is proceeding under either danger or caution speed control such speed restriction can be eliminated when the track is clear.

A further object is to provide such an

apparatus using, at spaced distances or intervals along the track, suitable control elements for the responsive means of the locomotive, said elements being differently energized or otherwise conditioned for different traffic conditions, such as clear, caution and danger, and the vehicle or locomotive equipment being controlled accordingly by the action of the responsive means in passing the control elements on the track.

A still further object is the provision of novel means for controlling the circuits of the electrical control elements of the track dependent on traffic conditions; a further object being the obtainment of different conditions of the control elements when there are vehicles on the track different distances ahead, such as one condition when the track is clear when a certain number of blocks ahead are unoccupied, a caution condition when a certain block ahead is occupied and a danger condition when the next block ahead is occupied; and a still further object, in this connection, is to so arrange the circuits of the control elements of the track that electrical current is not used for such elements unless a vehicle is travelling in a block, and then the control elements of such block only use electrical energy, providing clear or caution conditions exist.

Another object is the provision of a novel and improved run-down device operable in a practical and efficient manner.

A further object is the provision of a novel and improved reset device for the run-down device.

A further object is the provision of a novel and improved clearing device for removing the speed control restriction when clear track conditions exist.

It is also an object of the invention to improve this type of apparatus generally as well as in its details, to provide a practical and operative organization of correlated elements and devices, and to adequately supply the needs and requirements for automatic locomotive or train control without the objections incident to continuous and block-entrance initiated control apparatus and heretofore proposed.

With the foregoing and other objects in

view, which will be apparent as the description proceeds, the invention resides in the construction and combination of parts, as hereinafter described and claimed, it being understood that changes can be made within the scope of what is claimed, without departing from the spirit of the invention.

The invention is illustrated in the accompanying drawings, wherein—

10 Figure 1 is a diagrammatical view of the apparatus.

Fig. 2 is a similar view of a variation or modification.

15 *Normal running circuit.*

An electro-magnet 10 controls an air valve or other device, so that when said magnet is deenergized the brakes are applied, the steam, electrical or other power shut off, or both, so that such magnet must be kept energized in order that the locomotive can proceed. The locomotive-stopping magnet 10 is therefore disposed in a normal running circuit including the generator 11 or other source of electrical energy, magnet 10, switch 12, contact 13, clear-maintaining electro-magnet 14 normally holding the switch 12 against the contact 13, conductor 15, contact strip 16 engaged by a switch 17, a second contact strip 18 engaged by said switch 17, conductor 19, switch or brush 21, a contact strip 20 engaged by said switch or brush 21, and a conductor 22 leading from the strip 20 back to the generator 11. With this circuit closed the magnet 10 is energized so that the locomotive can proceed, and the clear maintaining magnet 14 is energized to hold the switch 12 against the contact 13, which is necessary if the train is to proceed without speed restriction, the magnet 14 when deenergized enforcing the speed control, as will herein-after more fully appear.

Run-down device.

45 The switch 17 is operated by a run-down device that will remove the switch 17 from the strip 16 and then from the strip 18 unless the device is reset. This run-down device, designated generally at 23, in the embodiment as shown, comprises a pivotally mounted lever 24 to which the switch 17 is secured, and the lever 24 has a weight 25 so that the lever will gravitate when free to do so. A rod 26 is slidable through a guide 27 with which the lever is provided, and projects beyond the end of the lever to engage a helix 28, which, as shown, is concaved or curved lengthwise about the pivot of the lever as a center, in order that the terminal of the rod 26 may follow the helix in the downward swinging movement of the lever. The helix has an annular flange or landing 29 at its lower end, on which the rod 26 can come to rest when the rod has followed the helix down to the lower end thereof, thereby

permitting the helix to continue revolving while the lever 24 remains in its lowermost position. The helix 28 is driven from a wheel 30 of the locomotive or other driving member which rotates in proportion to the speed and distance of travel of the locomotive, and any suitable reversing gear 31 is located between the wheel 30 and helix 28, so that said helix will rotate in the same direction when the locomotive travels in either direction, this being essential in order that the helix will travel in the same direction even though the locomotive may be turned around with either end foremost. Thus, the projecting end of the rod 26 bearing on the helix 28 will follow said helix down, as the helix rotates, whereby the lever 24 moves downwardly in proportion to the distance of travel of the vehicle, and the lever will move on down to its lowermost position unless reset.

The centrifugal speed governor 32 is geared, as at 33, to the helix 28, so that the governor is driven from the helix which retards the movement of the lever or member 24, and this assures that the helix or member 28 must be rotating if the governor is in operation. The switch or brush 21 is carried by the governor, being insulated therefrom, so as to be raised and lowered, and it will be noted that the conductors 19 and 22 of the circuit of the magnet 10 are connected by the strip 20 and switch 21 when the governor is in operation. The strip 20 is sufficiently short so that when the governor stops and gravitates, the switch 21 is removed from said strip, thereby disconnecting the conductors 19 and 22, which will open the circuit of the magnet 10 and stop the locomotive should the governor fail to operate while the locomotive is running. The gap between the strip 20 and switch 21 can be bridged, however, when an intentional stop is made by the engineer or motorman. Thus, the throttle lever or power control member 34 can be used to bridge such gap when said member is moved to shut off the power. As shown, the conductor 22 is connected to the lever or member 34, and a contact 35 is connected to the switch or brush 21, so that the lever 34 in being moved to initial position to shut off the power, will engage the contact 35, thereby forming a bridge between the strip 20 and switch 21. This will keep the circuit closed between the conductors 19 and 22 while the power is shut off. Therefore, when an intentional stop is made, even though the switch 21 moves away from the strip 20, the circuit of the magnet 10 is not opened at this point, but the circuit will be opened if the member 34 is advanced to remove it from the contact 35 and the governor 32 is not rotating sufficiently to raise the switch 21 against the strip 20. When the locomotive is start-

ed, the member 34 remains in engagement with the contact 35 for a sufficient interval to enable the governor to raise the switch 21 against the strip 20 before the member 5 34 is removed from the contact 35, but, when the power is applied fully and the member 34 removed from the contact 35, should the governor 32 fail to operate, the switch 21 not being returned to the strip 20, will open 10 the circuit and deenergize the magnet 10, thereby preventing the locomotive from proceeding with the governor defective. When the governor is in operation the helix 28 must be turning, for the operation of the 15 governor is dependent on the rotation of the helix, and this assures of the lever 24 being moved downwardly. Not only is the lever 24 moved downwardly by gravity, but the rod 26 engaging the helix will force the lever 20 downwardly, although it may have a tendency to stick.

Resetting device.

The lever 24 of the run-down device must be reset or raised before the switch 17 is removed from the strips 16 and 18, or speed restriction or stopping of the locomotive will be enforced by the mere travelling of the locomotive a given distance without the resetting of the run-down device occurring. In this way, the run-down device is operable to produce an ultimate caution or danger condition, unless the run-down device is reset or restored at intervals. The run-down device thus controls the circuit of the magnet 10 to produce a locomotive retarding or stopping condition, without any responsive control between the vehicle and track, should the locomotive proceed without proper impulses or indications being received from the track that controls the resetting device.

In the embodiment as shown, the resetting device comprises a solenoid or electromagnet 36 having the core or armature 37 to be raised when the solenoid is energized, and said core is connected by a link 38 with a lever 39 fulcrumed to the lever 24. The link 38 is connected to one arm of the lever 39 and the other arm of said lever 39 is pivoted to the rod 26, so that when the core 37 is raised, the lever 39 is swung to retract the rod 26 from the helix 28. The lever 24 has stops 40 to limit the movement of the lever 39 and rod 26 with reference to the lever 24, and a suitable spring 41 is provided to yieldingly project the rod 26 from the lever 24 to engage the helix. Should the rod 26 be broken off or should the spring 60 fail to project the rod, the lever 24 can gravitate at once, as soon as the solenoid 36 is deenergized, to produce a danger condition, so that the presence of the rod 26 and helix 28 is necessary to support the lever 24 65 for downward movement in proportion to

the distance of travel of the locomotive. When the solenoid 36 is deenergized, the weight of the core 37 is imposed on the lever 24 to assist in moving the lever downwardly. When the lever is in any position 70 and the solenoid 36 is energized, the core 37 being raised will first swing the lever 39 to retract the rod 26 from the helix 28, the spring 41 having only a slight tension, and the lever 24 is then raised back to its initial 75 or starting position.

Caution speed control circuit.

The contact strip 16 is sufficiently short so that when the lever 24 of the run-down device moves part way down, the switch 17 is removed from the strip 16, thereby opening the circuit through the clear maintaining magnet 14, so that the switch 12 drops and enforces a speed restriction or stopping of 80 the vehicle. Supposing the lever 24 to have moved downwardly sufficiently to remove the switch 17 from the strip 16, with the switch 17 still on the strip 18, there will be established a caution control circuit including the 85 generator 11, magnet 10, switch 12, contact 42 engaged by said switch when down, conductor 43, caution speed control contact strip 44, switch 45 carried by the governor 32, ground connection of the switch 45 to the 90 helix 28, rod 26, lever 24, switch 17, contact strip 18, conductor 19, switch 21, contact strip 20 and conductor 22. The strip 18 and switch 21 remain in the circuit of the magnet 10 when such caution speed control circuit is established. The switch 45 may be grounded directly to the lever 24, but, in grounding the switch 45 to the helix 28, the current must flow from the helix through the rod 26, so that if said rod fails to contact 95 with the helix, due to an accident in the mechanism, the circuit will be opened. The switch or brush 45 is raised and lowered by the governor, depending on the speed, and the strip 44 is of such length as to only be engaged by the switch 45 when the locomotive 100 is travelling below a predetermined speed, say fifteen miles per hour, so that if such speed is exceeded with the switch 12 down, the circuit will be opened between the strip 44 and switch 45, to deenergize the magnet 10 and retard the locomotive until the speed is reduced for the return of the switch 45 to the strip 44. Thus, the moment 105 the switch 12 is released from the magnet 14, the speed restriction for caution conditions will be established, requiring the locomotive to travel below the maximum speed for such condition. A caution condition in the vehicle equipment is thus established when the 110 run-down device has run down part way without being reset. The strip 18, and switch 21 and strip 20 are still in the circuit of the magnet 10, however, to break such circuit if the governor should stop or if the 115 120 125 130 135

switch 17 is removed from the strip 18 by the further downward movement of the lever 24 resulting in a danger condition.

Danger speed control circuit.

When the lever 24 moves downwardly to carry the switch 17 away from the strip 18, danger conditions are established in the vehicle equipment and a danger speed control circuit is established including the generator 11, magnet 10, switch 12, contact 42, conductor 43, caution speed control strip 44, switch 45, contact 46 engaged by the switch 45 when the governor has stopped, contact 47, normally gravitated switch 48, electromagnet 49, conductor 50, switch 51, conductor 19, switch 21, strip 20 and conductor 22. However, if the locomotive is in motion and the switch 45 is raised from the contact 46, said switch only engaging the contact when the governor has stopped, such circuit will remain open to require the stopping of the locomotive because of the magnet 10 being deenergized. Now, when the locomotive has been brought to a stop so that the switch 45 engages the contact 46, and the engineer or motorman closes the switch 51, such circuit will be established to energize the magnet 10 again whereby the locomotive can proceed, providing, under this danger condition, the engineer holds the switch 51 closed, thereby requiring him to be alert. Such circuit being closed will energize the magnet 49 and raise the switch 48 from the contact 47 into engagement with a contact 53, which is connected to a danger speed control contact strip 52 engaged by the switch 45 when the locomotive is travelling at a predetermined slow speed, say five or eight miles an hour or less. The strip 52 is sufficiently short so that the switch 45 will be removed therefrom as soon as such restricted danger speed is exceeded. The change of connection from the contact 46 to the danger speed control strip 52 is necessary to enable the locomotive to proceed, inasmuch as the switch 45 is raised from the contact 46 as soon as the vehicle moves. The circuit from the strip 44 to the conductor 50 now includes the contact strip 44, switch 45, contact strip 52, contact 53, switch 48 and magnet 49 holding the switch 48 raised. This enables the locomotive to proceed but if the restricted speed is exceeded, the switch 45 being removed from the strip 52, will open the circuit and deenergize the magnet 10. The magnet 49 will also be deenergized, letting the switch 48 drop into connection with the contacts 47 and 46, and the locomotive must again be brought to a stop before it can proceed further. A stop of the locomotive is therefore enforced whenever the maximum speed under danger conditions is exceeded, before the locomotive can move on. Also, the engineer must hold the switch 51 closed, so as to

be alert, to proceed under danger speed control, and if he releases the switch 51, the circuit is opened and the locomotive stopped. This requires the alertness of the engineer while under danger control.

70

When the caution speed control circuit is established, as hereinbefore described, the contact 13, magnet 14, conductor 15 and strip 16 are replaced by the contact 42, conductor 43, strip 44, switch 45 and ground 75 to the lever 24, and when the danger speed control circuit is established, the switch 17 being removed from the strip 18, the contact 13, magnet 14, conductor 15 and strip 16, together with the lever 24, switch 17 and strip 18, are replaced by the contact 42, conductor 43, strip 44, switch 45, contact 46 or strip 52, switch 48, conductor 50 and switch 51, the clear, caution and danger circuits all leading through the conductor 19, switch 21, strip 20 and conductor 22 back to the generator 11.

80

85

Resetting circuit.

The energization of the solenoid or magnet 36 for resetting the run-down device is controlled by a suitable responsive element or device carried by the locomotive or vehicle. In the embodiment as shown such responsive element comprises an armature 54 or other member magnetically responsive to magnetic fields created on the track, although the impulses or indications from the track to the locomotive can be obtained in any of the well known manners, there being different kinds of control and responsive elements available for accomplishing the same results. The armature 54 is carried by a weighted lever or switch 55, and when the armature is attracted to a magnet on the track, the switch 55 is moved against a contact 56. This response of the responsive element or armature is used for energizing the solenoid 36 to reset the run-down device, and means is provided whereby the solenoid 100 110 115 120 125 130 135 140 145 the contact strips 62 and 64, and the magnet 57 being energized, by the closing of the switch 55, even though for a slight instant, will pick up the switch 58 and remove it from the contact 59 to raise the switch against a contact 67 in the circuit of the solenoid 36. This closes the circuit of the solenoid including the generator 11, magnet 57, switch 58 held in raised position by the magnet, contact 67, conductor 66 including a solenoid 111 hereinafter described, solenoid 36, conductor 61 also connected to the solenoid, contact strip 62, switch 63, contact strip 64 and conductor 65. The response of the armature 54 will therefore first energize the magnet 57 to raise the switch 58 against the contact 67, which will close the circuit of the solenoid and such circuit will remain closed until the lever 24 is returned to its starting position, at which time the switch 63 being removed from the strips 62 and 64 will open the circuit. The solenoid 36 is deenergized and the magnet 57 is also deenergized to release the switch 58, thereby breaking the circuit at two points, and the lever 24 will be released to immediately start downward again. By this arrangement, the solenoid 36 will remain energized until it raises the lever 24, but the raising of the lever is accomplished quickly, and with a slow moving train said lever may be raised while the armature 54 is passing a track magnet, while with a fast moving train the armature 54 may have moved a short distance beyond the track magnet before the lever is completely raised, such variation, however, not being sufficient to affect or interfere with the working of the apparatus, due to the latitude of distance control as hereinafter pointed out.

Track circuits and control elements.

Disposed on the track at suitable spaced intervals are the electro-magnets 68 and 69 which alternate with one another along the center of the track. These electro-magnets are used for creating magnetic flux at the spaced points along the track for the attraction of the armature 54, although said electro-magnets may be substituted by other electrically operated or energized control elements or devices. Such electro-magnets or control elements are spaced apart a substantially uniform distance, there being an electro-magnet say every thousand feet or every few thousand feet, as may be decided upon when making the installation of the apparatus. Said magnets when energized produce magnetic fields in the path of the armature 54 which is responsive to the magnetic flux, so that the track control elements being energized will enable responses to be received by the vehicle equipment at intervals while the locomotive is moving along the track. The blocks may be of different

lengths and the longer blocks would naturally include a larger number of electro-magnets or control elements. As shown, the track is divided into the blocks A, B and C, and the rails are insulated between the blocks. An electro-magnet 70 has its terminals connected to the opposite rails in each block, and a battery or other source of electrical current 71 is also connected to the opposite rails in each block, which magnets and batteries may be those of the signal circuits as well known. When any block is occupied, the wheels and axles of a vehicle therein will connect the rails and produce a short-circuit, so that the corresponding magnet is deenergized. The magnets are designated 70, 70' and 70'' for the respective blocks A, B and C. The magnet 70 controls switches 72 and 73, the magnet 70' controls switches 74 and 75, and the magnet 70'' controls the switches 76 and 77, which are held raised when said magnets are energized.

The track circuits for each block are the same, and only the circuits for the block A will be described in detail, the circuits of the other blocks being duplicates thereof. The electrical energy for the track magnets or elements is furnished, as shown, by line wires 78 and 79 running along the track, and when the switch 73 is released, it will drop on contacts 82 and 83, the contact 83 being connected with the supply wire 78. The coils or windings of the magnets 68 of the block A are disposed in the conductor 80, and the coils or windings of the magnets 69 are disposed in the conductor 81, and those terminals of the conductors at the entrance end of the block (the direction of travel being toward the right as shown) are connected to the contact 82. When the block A is unoccupied, so that the magnet 70 can be energized, the switch 73 is raised from the contacts 82 and 83, thereby disconnecting the magnets 68 and 69 from the source of energy, so that such energy is not consumed or wasted. However, when the locomotive enters the block A, and the blocks B and C are unoccupied, so that the magnets 70' and 70'' are energized to raise the switches 74-75 and 76-77, the circuits of the magnets 68 and 69 of the block A are completed. One circuit includes the supply wire 78, contact 83, switch 73 (which has been dropped by the deenergization of the magnet 70 with the block A occupied), contact 82, conductors 80 and 81 in parallel, including the coils or windings of the two sets of electro-magnets, contact 84, switch 74 in raised position, and conductor 85 leading to the feed wire 79. The other circuit includes the wire 78, contact 83, switch 73, contact 82, conductor 80, contact 86, switch 75 in raised position, contact 87, conductor 89, contact 90, switch 76 in raised position, and

conductor 91 connected to the feed wire 79. The circuit of electro-magnets 68 therefore includes the switch 75 controlled by the magnet 70' of the next block ahead (block 5 B) and the switch 76 of the second block ahead (block C), while the circuit of the magnets 69 includes the switch 74 controlled by the magnet 70' of the first block ahead without including a switch controlled by the 10 magnet 70" of the block C. Consequently, if the blocks B and C are unoccupied, and the block A is occupied, the circuits of the magnets 68 and 69 in the block A will be closed and such magnets therefore energized. 15 If the block C is occupied, so that the magnet 70" is deenergized, the switches 76 and 77 are released, and this will disconnect the conductors 89 and 91, thereby opening the circuit of the magnets 68 in block A, so that 20 such magnets are deenergized while the magnets 69 in such block remain energized. This produces a caution track condition with a vehicle in the second block ahead. Should the block B be occupied, the magnet 70' being deenergized would release the switches 25 74 and 75, thereby opening the circuits of all of the magnets 68 and 69 in the block A and producing a danger traffic condition, there being a vehicle in the next block ahead. 30 Therefore, with all of the track magnets energized, clear traffic conditions exist, the track being unoccupied sufficiently far ahead to permit of unrestricted speed; when alternate magnets are deenergized, a caution traffic condition exists, with a block occupied ahead requiring the vehicle following to reduce its speed; and with all of the magnets deenergized a danger condition exists. Danger conditions will also exist if the 35 circuits or current fail. Under clear or caution conditions, however, the current will not flow through the track magnets unless the particular block is occupied, thereby affecting a saving in electrical energy by not 40 requiring energy for the track magnets excepting for the occupied blocks, and then only if clear or caution traffic conditions exist. Such track circuits constitute part 45 of the usual signal circuits, and it will be apparent that the track equipment may be used independent of or in connection with the wayside signal circuits. 50

Clearing device.

55 A clearing device is provided to return the switch 12 to the contact 13 when the rundown device has been reset and when successive track magnets are energized, requiring successive magnets 68 and 69 to be supplied with electrical current. In the embodiment shown this clearing device includes a bar or slide 100 movable loosely in guides 101, and adapted to gravitate when released, said slide when being raised two steps engaging a contact 102 connected to the con- 60 ductor 22. A clear restoring electro-magnet 103 is arranged to attract the switch 12 against the contact 13, and has a flexible connection 103' with the slide 100, so that when said slide engages the contact 102, the circuit 70 of the magnet 103 is closed including the generator 11, magnet 10, magnet 103, conductor 103', slide 100, contact 102 and conductor 22. In order to step up the slide 100, it has the teeth 104 and 105 to be engaged by 75 a dog 106 pivoted to a lever 107. The dog has an extension 108 crossing the lever and serving as a weight to swing the dog away from the slide, and the extension 108 is connected by a link 109 with the core or armature 80 110 of a solenoid or electro-magnet 111 disposed in the conductor 66 of the solenoid 36. Stop pins 112 and 113 are carried by the extension 108 to limit the movements of the dog 106 relatively to the lever 107. When 85 the solenoid 36 is energized to reset the rundown device, the solenoid 111 is energized at the same time to raise the core 110. The raising of the core 110 will first swing the extension 108 upwardly to move the dog 106 90 under the first tooth 104 of the slide, and the stop 113 striking the lever 107, will then cause said lever to be raised, as indicated in dotted lines, to raise the slide 100 one step. When the solenoids 36 and 111 are de- 95 energized the core 110 will drop, adding its weight to the weight of the dog 106 and lever 107 to swing the dog away from the slide and to swing the lever downwardly. Therefore, the slide 100 will drop down un- 100 less held in its first step position. 105 Means is provided for supporting the slide 100 in its first step position providing the locomotive is travelling under caution control. The slide 100 has a lug 114 to be engaged by a dog 115 having an armature 116 to be attracted and held by an electro-magnet 117. One terminal of the magnet 117 is connected to the conductor 19, and a conductor 118 connects the other terminal of 110 the magnet with a contact 119 having the companion contact 120, and the contact 120 is connected to the conductor 15. An insulated bridging switch 121 is carried by the switch 12 to engage contacts 119 and 120 115 when the switch 12 is released from the magnet 14, thereby closing the circuit of the magnet 117 when speed control is effective with the switch 12 down. The magnet 117 is simply in a shunt between the conductors 126 15 and 19, such circuit of the magnet 117 including the generator 11, magnet 10, switch 12, contact 42, conductor 43, strip 44, switch 45, ground through lever 24, switch 17, contact strip 16, conductor 15, contact 120, 123 switch 121, contact 119, conductor 118, magnet 117, conductor 19, switch 21, strip 20 and conductor 22. The magnet 117 will, when energized, attract the armature 116 and hold the dog 115 in a position to engage 130

under the lug 114 when the slide 100 is raised the first step, the lug 114 and dog 115 being rounded to throw the dog away from the slide should the slide gravitate with the magnet 117 deenergized, even though the dog should fail to swing away from the slide by gravity. In other words, the dog 115 can only hold the slide raised with the magnet 117 energized. Sufficient resistance 122 is disposed in the conductor 119 in advance of the connection of the magnet 117 with said conductor, to compel sufficient current to flow through the magnet 117 to keep said magnet energized, the resistance 122 and magnet 117 being in parallel in the circuit. Thus, with the locomotive running under caution control, with the switch 17 on the strip 16, the magnet 117 is kept energized to hold the armature 116 with the dog 115 in readiness to snap under the lug 114 should there be a response received from the track resulting in the energization of the solenoids 36 and 111. If the switch 17 remains on the strip 16 and a second response is received, so that the solenoids 36 and 111 are again energized, the tooth 105 being in the position where the tooth 104 is normally located, will result in the dog 106 engaging under the tooth 105 and raising the slide a second step to bring the slide 100 against the contact 102 so that the magnet 103 will be energized for raising the switch 12, and with the switch 17 still on the strip 16, the circuit through the magnet 14 is reestablished, thereby restoring the normal running circuit. However, whenever the switch 17 is removed from the strip 16, the circuit through the magnet 117 is opened, thereby releasing the armature 116 and letting the slide 100 drop, so that there must be two successive responses of the armature 54 with the switch 17 maintained in engagement with the strip 16, to obtain the clearing action. The arrangement is such that if two successive track magnets are energized the vehicle equipment will be cleared, although by using more lugs 114 and teeth on the slide 100 and increasing the distance between the slide 100 and contact 102, it may require three or more actuations to establish clear conditions.

Operation.

The apparatus, in the embodiment as shown, is operable for establishing clear, caution and danger conditions in the vehicle equipment, for the control of the locomotive accordingly, although other conditions may be provided for. The establishment of the several different conditions will be described separately.

Clear conditions.

When the blocks B and C are unoccupied then clear conditions exist in the block A, and when the locomotive enters such block

A, the magnet 70 being deenergized and the switch 73 dropped will close the circuits of the electro-magnets 68 and 69 in such block for resetting the run-down device at each resetting point of the track where the magnets are located.

Supposing the armature 54 to be approaching the first magnet 68, with the lever 24 moving downwardly, the armature 54 would pass over such energized first magnet 68, thereby bringing the switch 55 against the contact 56 and energizing the solenoid 36 to return the lever 24 to starting position. Now, as the armature 54 moves with the vehicle away from the first magnet 68 toward the first magnet 69, the lever 24 moves downwardly proportionately to the distance travelled. The distance D represents substantially the distance the vehicle must move before the lever 24 has moved downwardly sufficiently to remove the switch 17 from the strip 16, such distance being greater than the distance between the electro-magnets 68 and 69, there being a sufficient latitude to assure of a resetting of the run-down device occurring before the retarding condition will occur. The distance D' represents the distance of travel of the vehicle necessary before the switch 17 is removed from the strip 18 and such distance is sufficiently greater than double the distance between two adjacent track magnets, so that a resetting of the run-down device is assured, if proper, before a danger condition is established.

Now, with the vehicle travelling from the first magnet 68 to the second magnet 69, the lever 24 is moving downwardly, and when the armature 54 passes the first magnet 69, the switch 17 is still on the strip 16 but is ready to leave said strip shortly after the armature 54 leaves the first magnet 69. The magnet 69 being energized will attract the armature 54 to close the switch 55, thereby again energizing the solenoid 36 to return the lever 24 to starting position again without the switch 17 having moved off the strip 16. This same action occurs when moving from each track magnet to the next, and as long as the successive track magnets are energized, the run-down device is repeatedly reset to keep the normal running circuit closed, unless there is a failure of any of the circuits or other portions of the apparatus, failures being on the side of safety. During clear conditions, therefore, with all of the track magnets energized, the run-down device repeatedly moves toward a vehicle retarding position, but will be reset each time a resetting point of the track is passed if the corresponding track magnet is energized. When the normal running circuit is closed and the switch 12 raised, the switch 121 being removed from the contacts 119 and 120 will open the circuit of the magnet 130

117, so that the dog 115 is removed from the slide 100, and the slide 100 can be raised and lowered as the solenoid 111 is energized and deenergized with the solenoid 36. This will keep the working parts of the clearing device loosened up to avoid sticking or binding thereof.

Caution conditions.

- 10 With the block C occupied, caution conditions exist in the block A, inasmuch as the switch 76 being released to move away from the contact 90, will open the circuit of the magnets 68 in the block A, so that only 15 every other magnet in the block A will remain energized. In other words, the magnets 68 in the block A are deenergized and the magnets 69 energized for caution conditions.
- 20 Supposing the vehicle to be entering the block A with the armature 54 approaching the first magnet 68 and the lever 24 moving downwardly, when the armature 54 passes over the deenergized magnet 68, no response 25 of the armature or responsive element is possible, and the run-down device is therefore not reset, so that the lever 24 keeps on moving downward while passing the first magnet 68. When the distance D has been 30 travelled, the armature 54 having been moved beyond the first magnet 68, the switch 17 is removed from the strip 18, thereby opening the normal running circuit, which includes the magnet 14, and the magnet 14 is therefore deenergized to let the switch 12 fall down on the contact 42. A 35 caution condition is therefore established at once, including the caution speed control circuit. Such circuit comprises the generator 11, magnet 10, switch 12, contact 42, conductor 43, caution speed control strip 44, switch 45, ground connection through the lever 24, switch 17, strip 18, conductor 19, switch 21, strip 20 and conductor 22. If the 40 vehicle is travelling above the maximum caution speed, with the switch 45 above the strip 44, the circuit is opened and the magnet 10 deenergized to retard the movement, and when the switch 45 engages the strip 44, the circuit is closed to energize the magnet 10 so as to permit the vehicle to proceed, but the speed is limited to that allowed 45 under caution control. Such caution control will continue as long as the switch 12 is down against the contact 42, but a danger condition is not established providing the magnets 69 are energized. With the vehicle moving from the first magnet 68 to the first magnet 69 in the block A, the run-down 50 device not having been reset in passing the first magnet 68, the lever 24 continues to move downwardly, but the armature 54 reaches the first magnet 69 before the switch 17 is removed from the strip 18. Therefore, 55 if such magnet 69 is energized to attract the

armature 54, the solenoid 36 will be energized to reset the run-down device before a danger condition is established. When the armature 54 moves past the second magnet 68, which is also deenergized, the lever 24 will again move to caution position, as before, thereby repeating the caution producing effect, and the armature 54 reaches the second energized magnet 69 before the switch 17 is removed from the strip 18. Therefore, although the caution condition is repeated when alternate magnets are deenergized, a danger condition is not produced, and the locomotive must therefore proceed under the caution speed control.

Danger conditions.

When the block B is occupied, so that the magnet 70' is deenergized, the switches 74 and 75 moving downwardly will open the circuits of all of the magnets 68 and 69 in the block A, thereby producing a dangerous traffic condition. The caution and danger conditions in the vehicle equipment are obtained in succession in passing two deenergized track magnets. Thus, supposing the locomotive to be approaching the first magnet 68, which is deenergized, the armature 54 failing to respond will let the run-down device go to caution position after the armature 54 passes such magnet and has moved the distance B. The lever 24 continues its downward movement and after passing the next track magnet (first magnet 69), the locomotive having moved the distance D', the lever 24 moves completely down thereby removing the switch 17 from the strip 18. A caution condition is established as soon as a de-energized track magnet has been passed, as hereinbefore described, thereby retarding the movement of the vehicle and constraining the speed below a predetermined rate, and when the second track magnet is passed while deenergized, the run-down device will go to danger position, the circuit of the magnet 10 being opened to compel the locomotive to come to a stop. When the locomotive has come to a stop, so that the switch 45 is brought against the contact 46, and the engineer closes the switch 51 with the member 34 against the contact 35, the magnet 10 will be reenergized so that the train can proceed. The circuit includes the generator 11, magnet 10, switch 12, contact 42, conductor 43, contact strip 44, switch 45, contact 46, contact 47, switch 48, magnet 49, conductor 50, switch 51, conductor 19, switch 21, contact 35, member 34 in closed position against contact 35, and conductor 22. The lever 24 not being reset remains in its lowermost position while the train is running under danger control. The magnet 10 being reenergized will permit the vehicle to proceed, and the magnet 49 being simultaneously energized will raise the switch 48 away from

the contact 47 against the contact 53 which is connected to the danger speed control strip 52 engaged by the strip 45. This will change the control, when a stop is made, 5 from the stop contact 46 to the danger speed control strip 52. The vehicle can then increase its speed, but not above the speed limit for danger control, because if such speed is exceeded, the switch 45 being removed from the strip 52 will open the circuit of the magnet 10. Also, the magnet 49 being deenergized will release the switch 48 so that said switch will swing away from the contact 53 back against the contact 47, 10 again compelling the vehicle to come to a stop before it can proceed. It is also necessary, when proceeding under danger control, for the engineer to hold the switch 51 closed, thereby assuring that he is alert for 15 making a stop immediately whenever necessary, even though travelling at a slow speed. These conditions will prevail as long as the track magnets are deenergized and the lever 24 remains in its lowermost position, there being nothing to reset the run-down device. 20

It will therefore be apparent from the foregoing description that whenever the armature 54 passes a single deenergized track magnet, a caution condition is established, and such condition will be continued when alternate magnets are energized and the others deenergized; and whenever two successive deenergized track magnets are passed a danger condition is established. 30 Such conditions are established at any point of the track, to obtain almost completely continuous control. The speed restriction for caution conditions permits of higher speed than under danger control, to 35 facilitate traffic, inasmuch as the most stringent speed restriction is not necessary under caution conditions as it is under danger conditions. Furthermore, the vehicle equipment can be restored, whenever passing an energized track magnet, from a danger to a caution condition, and can be restored to clear whenever passing two successive energized track magnets, as will presently appear. 40

Clearing operation.

Supposing the locomotive to be travelling under danger control with the lever 24 completely down and the switch 48 against the contact 53, as hereinbefore described, whenever the armature 54 passes an energized track magnet, the track must either be clear or under caution condition ahead. Therefore, whenever the armature 54 passes an energized track magnet, to close the switch 55, the solenoid 36 is energized to return the lever 24 to initial or starting position, and as soon as the switch 17 is returned to the strip 18, the danger control contact 46 and strip 52 are removed from the circuit of 55

the magnet 10, and a caution condition is produced, the circuit of the magnet 10 extending through the switch 12, contact 42, conductor 43, strip 44, switch 45, ground to lever 24, switch 17, strip 18, conductor 70 19, switch 21, strip 20 and conductor 22. A caution condition is thus obtained when travelling under danger control past a single energized track magnet. If alternate magnets are energized and the others deenergized, the vehicle must proceed under caution control, as hereinbefore described, the lever 24 being returned to starting position when passing the magnets 69, thereby keeping the switch 17 on the strip 18. 80

When proceeding under caution control, either by a stepping down from clear to caution, or by stepping up from danger to caution, the vehicle equipment is cleared automatically, but not unless two successive track magnets are energized to assure of the track being clear. 85

When proceeding under either caution or danger speed control, the switch 12 is down against the contact 42, thereby bringing the switch 121 against the contacts 119 and 120, so that the magnet 117 is in parallel with the resistance 122, thereby energizing the magnet 117 and attracting the armature 116 to hold the dog 118 in the path of the lug 114. The circuit of the magnet 117, however, includes the short strip 16, so that the lever 24 must not move to caution position, or else the magnet 117 is deenergized to release the slide 100. This requires the successive responses of the vehicle equipment to two energized track magnets to obtain a clear condition, requiring the magnets 68 and 69 to be energized. Thus, when travelling under caution control, although the magnet 117 is energized while the switch 17 is on the strip 16, the switch 17 is removed from the strip 16 whenever passing a deenergized track magnet, thereby deenergizing the magnet 117 and preventing a clear condition being obtained because of a caution condition persisting. However, when the first track magnet is passed by the armature 54, with such magnet energized, the closing of the circuit of the solenoids 36 and 111 will return the lever 24 to starting position, thereby setting the vehicle equipment to caution condition if a danger condition existed, and if the armature 54 passes the next track magnet, with such magnet energized, the lever 24 is reset to starting position again before the switch 17 is removed from the strip 16. Thus, with the track clear and all track magnets energized, the lever 24 will be returned twice in succession with the switch 17 remaining on the strip 16 to keep the magnet 117 energized. 115

Supposing, therefore, that the lever 24 is returned twice, with the switch 17 remaining 130

on the strip 16 to keep the magnet 117 energized, then the vehicle equipment will be cleared by the return of the switch 12 to the contact 13, as follows: The first time 5 the solenoid 36 is energized, the solenoid 111 being simultaneously energized will raise the core 110, thereby first swinging the dog 106 under the tooth 104, and then raising the lever 107 to raise the slide 100 10 one step, moving the lug 114 past the dog 113. The slide 100 will therefore be held in its first step position, the magnet 117 remaining energized to hold the dog 113 under the lug 114, and the tooth 105 will then be in the position 15 originally occupied by the tooth 104. The solenoids 36 and 111 being deenergized when the switch 63 is removed from the strips 62 and 64, will let the dog 106 and lever 107 drop. When the solenoids are energized 20 the second time, the step-up operation is repeated, and the dog 106 engages under the tooth 105 so as to raise the slide 100 a second step, thereby bringing the slide against the contact 102 which results in the 25 clearing of the vehicle equipment by closing the circuit of the clear restoring magnet 103 including the generator 11, magnet 10, magnet 103, conductor 103', slide 100, contact 102 and conductor 22. The magnet 103 30 raises the switch 12 against the contact 13, and the lever 24 being at least partly raised with the switch 17 on the strip 16, will restore the normal running circuit for clear conditions. The slide 100 will drop back to 35 its lowermost position because of the deenergization of the solenoids 36 and 111, and the switch 12 being raised will open the circuit of the magnet 17, whereby the dogs 106 and 115 will swing away from the slide by 40 gravity, or, when the solenoid 111 and magnet 117 are deenergized, the weight of the slide 100 may be sufficient to force the dogs out of engagement therewith should the dogs fail to swing away from the slide of themselves. 45

Summing up the operation briefly it will be observed that when all of the track magnets are energized, the locomotive can proceed without speed restriction; when a track magnet is passed while deenergized a caution condition is immediately established, and such condition will be maintained with alternate track magnets energized and the others deenergized; when two successive track magnets are passed while deenergized the vehicle equipment will go to danger condition, enforcing a slower speed than when under caution condition; when proceeding under danger control and an energized track magnet is passed, the vehicle equipment will step up to caution control; and when under either danger or caution speed control and two energized track magnets are passed in succession, the vehicle equipment will step up to a clear condition. Such conditions can

be established while the locomotive is moving in the block, in order to provide almost continuous control, for purpose of safety in retarding or stopping the locomotive, even when it has entered a block, when a caution or danger condition presents itself, and for the further purpose of facilitating traffic by removing the speed restriction, even before reaching the end of the block, when caution or clear track conditions exist. Although the present apparatus is not, strictly speaking, continuous control it has the advantages thereof to a marked degree, without the disadvantage of using a sensitive detector for detecting alternating or other electrical current flowing in the rails, or the like. The apparatus, although somewhat intermittent in character, is not like the prevailing or known types of intermittent or block entrance initiated control apparatus in which the several 75 conditions can only be obtained at control stations. The present apparatus is therefore a compromise between the present known continuous control and the intermittent or block entrance initiated control, having advantages of both and eliminating disadvantages of each of them. By using the inductive elements on the track and vehicle, contact devices are eliminated, although they may be used, so far as the control of the vehicle equipment is concerned, the switch 55 or its circuit being readily closed by different mediums available in the prior art. The inductive means for control of the vehicle equipment from the track, however, 80 is preferable, because of the elimination of contact devices which are subject to jars and shocks, breaking off and other accidents, as well as constituting objectionable obstructions, while inductive devices between the 85 track and vehicle can have clearances of several inches, without physical contact, and may be removed sufficiently from the line of clearance between the track and vehicle so as not to constitute objectionable obstructions, either on the track or on the vehicle. 90

Modification.

In Fig. 2 there is illustrated a modified arrangement by means of which caution or 115 danger conditions can be established immediately when passing a reset point of the track with the track magnets deenergized accordingly, and also providing for the immediate clearing of the vehicle equipment 120 when passing a single reset point of the track with the track magnets energized accordingly. Thus, instead, as in the first form, of stepping from clear to caution and then to danger, the second form can step from a clear condition to either caution or danger and can step back from a danger condition to either caution or clear, requiring only one step for any change of conditions. This is obtained by using, in lieu of the 125 130

step-up clearing device of Fig. 1, two responsive elements or armatures 54' and 54'', spaced transversely of the track, with the electro-magnets 68' and 69' on the track arranged in pairs spaced apart transversely. The magnets and armatures may be located between the rails, as shown, or outside of the rails. The track circuits are substantially the same as in Fig. 1, the circuits of all magnets 68' and 69' in block A being opened when the magnet 70' is deenergized by the occupancy of block B, whereas when block C is occupied, the switch 76 opening will open the circuit of the magnets 69' in block 15 A but the circuit of the magnets 68' will remain closed, both circuits, or the single circuit, only being closed when the block A is occupied to release the switch 73. However, instead of the track magnets being 20 alternated as in Fig. 1, they are arranged in two longitudinal series side by side in pairs, requiring two magnets at each reset point of the track. In this arrangement as shown, the magnets 68' and armature 54'' 25 are for caution conditions, and the magnets 69' and armature 54' are for clear conditions, danger conditions existing when all track magnets are deenergized. This general idea is the same as in Fig. 1, wherein all 30 track magnets are deenergized for danger conditions, part deenergized and the rest energized for caution conditions, and all magnets energized for clear conditions.

A caution condition is established by the 35 response of the armature 54'' to an energized magnet 68' without the armature 54' moving while a clearing condition is obtained by the response of both armatures 54' and 54'' to a pair of energized magnets 68' and 69', the 40 clear restoring magnet 103 being controlled by the response of the armature 54', and the circuit of the clear maintaining magnet 14 being broken by the response of the armature 54''.

The operation is, in general respects, the same as with the first form of apparatus, and a brief description will no doubt suffice.

The normal running circuit includes the generator 11, magnet 10, switch 12, contact 50 13, magnet 14, conductor 15', blade 92 of a reversing switch, contacts 16'' bridged by the armature 54'', another blade 94 of the reversing switch, conductor 95, ground through the helix 28 and lever 24, switch 17, contact strip 18, conductor 19, switch 21, strip 20 and conductor 22.

The vehicle must travel the distance D, that is, from one pair of track magnets beyond the next pair, before the lever 24 moves 60 completely down to remove the switch 17 from the strip 18. A danger condition is only established when the lever 24 moves completely down to move the switch 17 away from the strip 18, and, if the vehicle moves 65 past a pair of track magnets, both of which

are deenergized, then the run-down device will go to danger position, and the circuit, the same as in Fig. 1, will include the generator 11, magnet 10, switch 12, contact 42, conductor 43, caution strip 44, switch 45, 70 contact 46 with the vehicle stopped and the switch 45 down, contact 47, switch 48, magnet 49, conductor 50, switch 51 held closed by the engineer, conductor 19, switch 21, strip 20 and conductor 22. The same speed control is therefore obtained as in the first form under danger conditions, the vehicle being permitted to proceed slowly after having come to a stop. 75

Under clear conditions, the blocks B and 80 C unoccupied, and the vehicle travelling in the block A, the magnets 68' and 69' in block A are all energized, and both armatures 54' and 54'' are attracted when passing a pair of energized track magnets. The 85 armature 54'' being moved away from the contacts 16'' will break the circuit of the magnet 14 momentarily, but the switch 55' of the armature 54' being moved against the contact 56', will energize the magnet 103 90 while the magnet 14 is deenergized, to hold the switch 12 against the contact 13, inasmuch as the removal of the switch 12 from the contact 13 would result in speed control being enforced. Thus, with both armatures 95 attracted by the track magnets, there is closed a circuit including the generator 11, magnet 57, switch 58, contact 59, conductor 60', blade 96 of the reversing switch, contact 56'', switch 55'' of the armature 54'', 100 conductor 61' connected to both switches 55' and 55'', strip 62, switch 63, strip 64 and conductor 65. Another circuit includes the generator 11, magnet 57, switch 58, conductor 97, magnet 103, conductor 98, blade 99 105 of the reversing switch, contact 56', switch 55', conductor 61', strip 62, switch 63, strip 64 and conductor 65. There is sufficient resistance 124 in the conductor 60' to compel part of the current to flow through the 110 magnet 103, when both armatures respond to the track magnets, to assure of the magnet 103 holding the switch 12 while the magnet 14 is momentarily deenergized, so that when the armatures 54' and 54'' return, after 115 passing the track magnets, the circuit of the magnet 14 will be restored at the contacts 16'' with the switch 12 remaining against the contact 13. The magnet 57 being energized will attract the switch 58 and move it against the contact 67, thereby closing the circuit of the solenoid 36, the same as in the first form, to return the lever 24 to starting position, and the removal of the switch 63 from the strips 62 and 64 will open the circuit of said solenoid and magnet 57. Clear 125 conditions are thus preserved when passing a pair of energized track magnets, and the run-down device is reset for a repeated operation. 130

When caution conditions exist, with the block C occupied, and the vehicle moving in block A, the circuit of the track magnets 69' in block A is opened, so that only the magnets 68' in such block are energized. Therefore, when passing a reset point of the track, the armature 54" will be attracted by an energized magnet 68', but the magnets 69' being deenergized will result in the armature 54' remaining against the contacts 16'. Therefore, although the run-down device is reset by the closing of the circuit including the generator 11, magnet 57, switch 58, conductor 60, blade 96, contact 56", switch 55", conductor 61', strip 62', switch 63, strip 64 and conductor 65, the circuit of the magnet 103 is not closed because of the failure of the switch 55' to move against the contact 56'. The run-down device is reset, but the magnet 103 not being energized when the armature 54" is removed from the contacts 16" will let the switch 12 drop from the contact 13 against the contact 42. This produces a caution condition, and, as hereinbefore stated, if neither armature of the vehicle equipment responds to an energized track magnet, then the solenoid 36 is not energized and the run-down device will go to danger position.

When proceeding under caution control, the switch 17 remains on the strip 18, the run-down device being reset at each reset point of the track, and the switch 12 is against the contact 42, and when proceeding under danger control the switch 12 is against the contact 42, the switch 17 removed from the strip 18, and the switch 45 engaging the strip 52 with the switch 48 against the contact 53. A caution condition is preserved when passing the track magnets with the magnets 68' energized and the magnets 69' deenergized, and a danger condition will continue with all track magnets dead.

The vehicle equipment can be cleared, when proceeding under either caution or danger control, when passing a pair of track magnets which are both energized, the vehicle equipment moving with one step to clear condition from either caution or danger condition. Thus, when both armatures 54' and 54" respond to the two energized track magnets, the solenoid 36 is energized to return the lever 24 to starting position, thereby assuring of the switch 17 being in engagement with the strip 18, and the magnet 103 is energized to pick up the switch 12 and return it to the contact 13. This will restore the normal running circuit, the armature 54" being returned to the contacts 16" when the armatures have passed the track magnets, so that the circuit of the magnet 14 is closed at the contacts 13 and 16" when the switch 55' is removed from the contact 56' to de-energize the magnet 103, the magnet 14

holding the switch 12 when the magnet 103 becomes deenergized.

When the locomotive is turned around so as to travel with its other end forward, the connections with the armatures 54' and 54" and their switches are reversed. The reversing switch blades 92, 94, 96 and 99 are connected to the reversing lever 123 of the locomotive, and when such lever is moved to reverse the locomotive, the blades 75 92 and 94 connect the conductors 15' and 95 with the contacts 16' engaged by the armature 54', and the blades 96 and 99 will connect the conductors 60' and 98 with the contacts 56' and 56", respectively, so that the armature 54' now controls the circuit of the magnet 14 while the switch 55" controls the circuit of the magnet 103.

Having thus described the invention, what is claimed as new is:—

1. Vehicle controlling apparatus comprising in combination with a track divided into blocks; two sets of control elements in each block and each including a series of control elements located at intervals along the track in the block; means controlling said control elements of each block and controlled by traffic conditions for rendering both sets of control elements operative under clear conditions, one set operative and the other set 85 inoperative for caution conditions, and both sets inoperative for danger conditions; the control elements of the two sets being associated throughout each block; a vehicle-carried run-down device operable whenever the vehicle is in motion for obtaining danger vehicle conditions when the vehicle has travelled a distance greater than the distance between the control elements of one set; and vehicle-carried means controlled by said control elements and controlling said run-down device and operable when responding to control elements with both sets operative to reset said run-down device and maintain clear vehicle conditions, and operable when responding only to the control elements of the operative set, with the other set of elements inoperative, to reset said run-down device and maintain caution vehicle conditions.

2. Vehicle controlling apparatus according to claim 1 wherein the lastnamed means has provisions from changing from danger to caution or clear vehicle conditions or from caution to clear vehicle conditions depending on passing the control elements of 100 both sets with one set or both sets operative.

3. Vehicle controlling apparatus comprising in combination with a track divided into blocks; two sets of control elements in each block and each including a series of control 115 elements located at intervals along the track within the block, with the control elements of the two sets associated throughout the block; means controlled by traffic conditions and controlling said control elements of each 120

- block for rendering both sets of elements operative for clear conditions, one set operative and the other set inoperative for caution conditions, and both sets inoperative 5 for danger conditions; a vehicle-carried run-down device operable whenever the vehicle is in motion for obtaining a danger vehicle condition whenever the vehicle has travelled a distance greater than the distance between 10 the control elements of one set; responsive means on the vehicle cooperable with and controlled by said control elements; and means controlled by said responsive means and controlling said run-down device for resetting said device and maintaining clear vehicle conditions when passing control elements with both sets operative, and for resetting said device and maintaining caution vehicle conditions when passing the control 15 elements with one set operative and the other set inoperative.
4. Vehicle controlling means according to claim 3 wherein the lastnamed means has provisions from changing from danger to 20 caution or clear vehicle conditions or from caution to clear vehicle conditions depending on passing control elements of both sets with one set or both sets operative.
5. Vehicle controlling apparatus includ- 25 ing a run-down device on the vehicle operable whenever the vehicle is in motion for obtaining an ultimate vehicle condition, control elements located at intervals along the track, means on the vehicle cooperable with 30 said elements, means controlled by said first-named means when passing successively operative control elements for intermittently resetting the run-down device to maintain another vehicle condition, means controlling 35 said elements and arranged for rendering alternate control elements operative and others inoperative for one track condition, and means operable, when said first-named means successively passes alternately operative and inoperative control elements, to es- 40 tablish another vehicle condition.
6. Vehicle controlling apparatus accord- 45 ing to claim 5 and also including in the combination, means operable, while the vehicle is proceeding under the firstnamed or lastnamed vehicle condition, and when the first-named means passes two operative control elements in succession, to reestablish the secondnamed vehicle condition.
7. Vehicle controlling apparatus includ- 50 ing a run-down device on the vehicle operable whenever the vehicle is in motion for obtaining an ultimate danger vehicle condition, control elements located at intervals along the track, means on the vehicle co- 55 operable with said elements, means controlled by said first-named means when passing successively operative control elements on the track for intermittently resetting the run-down device to maintain a clear vehicle 60 condition, means controlling said elements and arranged for rendering alternate elements operative and the others inoperative for a caution track condition, to let the run-down device run down farther than when all control elements are operative, said run-down device being 65
- condition, means controlling said elements and arranged for rendering alternate control elements operative and the other control elements inoperative for a caution track condition, and means operable, when the first-named means successively passes alternately operative and inoperative control elements to establish a caution vehicle condition. 70
8. Vehicle controlling apparatus accord- 75 ing to claim 7 and also including in the combination, means operable, while the vehicle is proceeding under the danger or caution vehicle condition, and when the first-named means passes two operative control elements 80 in succession, to reestablish the clear vehicle condition.
9. Vehicle controlling apparatus includ- 85 ing a run-down device on the vehicle operable whenever the vehicle is in motion, control elements located at intervals along the track, means on the vehicle cooperable with said elements, means controlled by said first-named means when same passes successively operative control elements for inter- 90 mittently resetting the run-down device to maintain one vehicle condition, means controlling said elements and arranged for ren- dering alternate elements operative and the others inoperative for one track condition, to let the run-down device run down farther than when all control elements are operative, said run-down device being arranged to obtain an ultimate vehicle condition when the first-named means has passed two inoperative control elements in succession, and means for establishing another vehicle condition when said device runs down only part way when passing the control elements with alternate elements operative and the other elements inoperative. 95
10. Vehicle controlling apparatus accord- 100 ing to claim 9 and also including in the combination, means operable, while the vehicle is proceeding under the firstnamed or lastnamed vehicle condition, and when the first-named means passes two operative control elements in succession, to reestablish the firstnamed vehicle condition. 105
11. Vehicle controlling apparatus includ- 110 ing a run-down device on the vehicle operable whenever the vehicle is in motion, control elements located at intervals along the track, means on the vehicle cooperable with said elements, means controlled by said first-named means when same passes successively operative control elements for inter- 115 mittently resetting the run-down device to maintain a clear vehicle condition, means controlling said elements and arranged for rendering alternate elements operative and the others inoperative for a caution track condition, to let the run-down device run down farther than when all control elements are operative, said run-down device being 120
- 125
- 130

arranged to obtain an ultimate danger condition when the firstnamed means has passed two inoperative control elements in succession, and means for establishing a caution vehicle condition when said device runs down part way when passing the control elements with alternate elements operative and the other elements inoperative.

12. Vehicle controlling apparatus according to claim 11 and also including in the combination, means operable, while the vehicle is proceeding under danger or caution vehicle condition, and when the firstnamed means passes two operative control elements in succession, to establish the clear vehicle condition.

13. Vehicle controlling apparatus according to claim 11 and also including in the combination, means for reestablishing the clear vehicle condition including a member to be stepped up to obtain the clearing condition, means for advancing said member step by step when the run-down device is reset intermittently, and means for maintaining said member in advanced position as long as said device does not run down such farther distance as when passing an inoperative control element. 20 25
